(57) **CLAIM**

We claim the ornamental design for a gum tin, as shown and described.

DESCRIPTION

FIG. 1 is a front perspective view of my new gum tin, with the hinged cover shown in a first closed position;

FIG. 2 is a front perspective view thereof, with the cover shown in a second, partially open position;

FIG. 3 is a side elevational view of one side thereof;

FIG. 4 is a side elevational view of the opposite side thereof;

FIG. 5 is a top plan view thereof;

FIG. 6 is a bottom plan view thereof;

FIG. 7 is a rear elevational view thereof; and,

FIG. 8 is a front elevational view thereof.
